PRODUCTION OF CHLORATES AND CHLORITES OF DIFFERENT METALS

Clifford A. Hampel, Harvey, Ill., assignor to Car-
dox Corporation, Chicago, Ill., a corporation of
Illinois

Application April 2, 1946, Serial No. 659,043

13 Claims. (Cl. 23—85)

1 This invention relates to a new process for the production of a chlorate and a chlorite.

It has been known heretofore that a chlorate and a chlorite of the same metal can be produced by the absorption of chlorine dioxide by an alkaline compound of that metal. For example, if potassium chlorate and potassium chlorite are to be produced, potassium hydroxide has been employed as the alkaline compound. The equation which illustrates this reaction is:

This prior known process has possessed several inherent disadvantages. For example, there may be numerous commercial and economic reasons why a particular manufacturer may want to produce for use or sale a chlorate and a chlorite of a different metal. To accomplish this desired result with the prior known process, it is necessary to carry out this process twice, using one metal alkali to produce the desired chlorate in one process operation and using another metal alkali in the second process operation to produce the desired chlorite of that metal. Therefore, four products are formed, although only two really are desired.

Another inherent disadvantage of the prior known process is that it is often extremely difficult or even impossible to effect by practical commercial means the separation of the chlorate and the chlorite of the same metal. Consequently, after practising two different processes to obtain four products, only two of which are really desired, the manufacturer has been confronted with the additional problem of separating out the two desired products.

Still another disadvantage of the prior known process is that the metal introduced appears half as the chlorate and half as the chlorite. This is objectionable if the metal is an expensive one as potassium, because it may be desired that all of it appear as the chlorate.

It is a primary object of this invention to provide a process for the production of a chlorate and a chlorite of a different metal in which the chlorate and the chlorite can be selected in accordance with the particular commercial needs of a given manufacturer.

It is a further important object of this invention to provide a process by means of which a desired chlorate and a desired chlorite can be produced, and in which the chlorate and the chlorite thus produced can be obtained by the

use of less expensive materials than the corresponding metal base or bases.

A further primary object of this invention is to provide a process by means of which a chlorate and a chlorite of a different metal are produced and which are readily separable by known commercial facilities.

A specific object of this invention is to provide a method of producing a chlorate and a chlorite of a different metal, in which one or the other is considerably less soluble in the same system, thus making them more readily separable.

Another specific object of the invention is to provide a process for producing a chlorate and a chlorite of a different metal in which substantially all of a particular cation introduced into the system, and which is capable of forming the chlorate or chlorite, is utilized in the production of the chlorate or chlorite which is desired.

Another specific object of the invention is to provide a process for the production of a chlorate and a chlorite of a different metal by which certain raw materials can be employed for producing one of the desired products which are different

from and less expensive than the base which is normally employed to produce that product. The use of less expensive materials is made possible by employing the salt of the metal of the desired chlorate or chlorite, which salt is less expensive than the corresponding base, and the base of the metal of the chlorate or chlorite desired, whereby the thus combined salt and base materials will introduce only a foreign anion, which anion will form a salt with the base cation which is less soluble in the system than the chlorate and/or chlorite produced.

Other objects and advantages of the invention will become apparent during the course of the following description:

As has been pointed out above, and as is specifically illustrated in Equation a, it has been known that the chlorate and chlorite of a given metal can be produced by reacting chlorine dioxide with the base of that metal. In accordance with the present invention, substantially equivalent quantities of a chlorate and a chlorite of different metals are produced. For example, potassium, sodium, lithium, barium, calcium, strontium, or magnesium chlorate can be produced in a process simultaneously with the production of a chlorite of a different one of these metals.

In general, the process of the present invention involves, first, the reaction of chlorine dioxide with a metal base and, second, the addition of a

salt or salts to the products of the first reaction. The process may be carried out in different ways, but they have in common the fact that the salt or salts which are added, are introduced into the system after the interaction between the chlorine dioxide and the metal base is substantially completed and before any separation of the products of that interaction is effected. Also, although different procedures and ingredients may be employed in practicing the invention, they have the common advantage that all or substantially all of one of the metals which is introduced, appears either as the chlorate or the chlorite.

That the results of the present invention can be obtained by this subsequent addition of certain ingredients to the system, is surprising because of the large number of components which are in the system. It would be expected that due to the large number of components in the system, it would not be possible to obtain a definite set of products, but in carrying out the present invention it has been found that the same high percentage of products is formed which would be formed if a prior separation had been carried out with respect to the products immediately resulting from the chlorine dioxide absorption.

One mode of carrying out the process of the present invention is to first absorb chlorine dioxide in an alkali which has the metal of the desired chlorite but not that of the desired chlorate, the metal of the desired chlorate being introduced as a salt. It may be pointed out here that an important advantage of this procedure is that an alkali may be employed which is considerably less expensive than the alkali which would have to be employed if the desired chlorate were to be produced by the process represented by equation (a). For example, if it is desired to produce potassium chlorate, instead of utilizing a relatively expensive potassium alkaline compound, the invention comprehends the employment of a sodium alkaline compound for the production of the chlorate ion. After the reaction has proceeded until the alkali has been neutralized and sodium chlorate and sodium chlorite have been produced, a potassium salt is added to these mixed reaction products and this will result in the formation of the desired potassium chlorate. These reactions are represented by the equations:

In equation (b), sodium hydroxide is used, but it is to be understood that any alkali, as an oxide, hydroxide, or carbonate may be employed, the hydroxide being used for illustrative purposes.

The term "hydroxide" as used in the claims embraces the introduction of oxides of the named metals into the system since oxides will inherently form the hydroxides of the named metals in an aqueous medium. Also, it is to be understood that the metal of this alkali should be that of the desired chlorite and for this reason it may be any one of the alkali metals, alkaline earth metals, or magnesium, sodium being selected merely to illustrate one example of the invention. In addition, it should be understood that the salt used to introduce the metal of the desired chlorate need not be a chlorite as shown in equation c, but may have another anion as, for example, the sulfate, phosphate, or nitrate ion. The metal of this salt should, however, be that of the desired chlorate and this may be a dif-

ferent metal selected from the above class from which the metal of the alkali is selected.

It will be observed from Equations b and c that the salt which is added for the purpose of introducing the metal ion, whose chlorate is desired, should be added in an amount equivalent to one-half of the alkali which is reacted. By adding this relative quantity of the salt having the metal whose chlorate is desired, its cation is present in an amount equivalent to the amount of chlorate ion which is formed from the chlorine dioxide. Thus, as will appear from a combination of Equations b and c, all of the potassium ion and all of the chlorate ion which is in the system will be combined to form potassium chlorate.

None of this metal of the introduced salt will, therefore, appear as the chlorite, and none of the chlorate ion which is formed will carry with it a cation other than that of the introduced salt. In obtaining certain chlorates, it is necessary to observe certain precautions in the selection of the ingredients. For example, the potassium ion should not be introduced into the system, if the chlorate of some other metal is desired. Also, the salt used should not be a sulfate, for example, if the chlorate desired is that of calcium or barium.

If a chlorite is to be utilized in carrying out the process represented by Equations b and c, this chlorite may be obtained by carrying out a separate chlorine dioxide absorption reaction. After the alkali used in this separate absorption reaction is neutralized, and before any separation of the reaction products is effected, they are combined with the reaction products resulting from the first absorption reaction. This is represented by the equations:

From Equations d, e, and f it will be observed that equal amounts on an equivalent basis of the two alkalis are employed. This results in the production of equivalent amounts of chlorate and chlorite ions in the separate absorption reactions, so that all of the one metal will appear as the chlorate and all of the other metal will appear as the chlorite. It is not necessary that the alkalis employed in Equations d and e have the same anion, as, for example, one may be a hydroxide and the other may be a carbonate. The precaution referred to in connection with Equations b and c should, however, be observed in the selection of the anions and cations.

If, in carrying out the process according to Equations b and c, the introduced salt is not a chlorite, but has another anion, it is convenient to select it so that the foreign salt product which is formed will be of a quite different solubility from the chlorate and chlorite. Thus, if the alkali employed is a calcium compound, it would be advisable to add potassium sulfate to introduce the potassium ion. The calcium sulfate which is then formed may be easily separated from the chlorite and chlorate. It should be understood, however, that if this foreign salt product is more soluble than calcium sulfate, it may still be separated from the chlorate and chlorite by appropriate separation means.

However, the invention contemplates the selection of such ingredients that the foreign salt product which is formed will be recoverable with either the chlorate or the chlorite. This will be

advantageous in some instances as this foreign salt will serve as a diluent. For example, by employing sodium hydroxide and potassium sulfate, the sodium chlorite recovered can be left diluted with sodium sulfate, if desired.

In carrying out the process of the invention according to a second mode, the alkali is used of the metal whose chlorate is desired, and after its absorption of chlorine dioxide until neutrality is reached, a salt of a different metal is added to the system. The cation of this salt should be the metal whose chlorite is desired. It is of particular benefit in carrying out this procedure to employ a chlorate as the salt since this will result in the appearance of all, or substantially all, of the metal of the alkali as the final chlorate product. For example, if it is desired to obtain potassium chlorate by the use of potassium hydroxide, all of the potassium introduced into the system as the hydroxide may be caused to appear as the chlorate by adding sodium chlorate in an amount equivalent to the chlorite formed. This process takes place according to the equations:

In equation *g*, a hydroxide is employed as the alkali, but instead, an oxide, or carbonate may be employed. Also, in Equation *h* sodium has been introduced by the added salt, but this metal may be selected from the alkali metals, alkaline earth metals, or magnesium, it being understood that this metal should be selected so as to form the desired chlorite. The precautions discussed above in reference to Equations *b* and *c* as to the selection of the cations and anions in the system must, however, be observed.

It has been noted that the salt used to introduce the metal of the desired chlorite need not be a chlorate. If it is not a chlorate, the foreign salt product which is formed may be separately recovered or it may be recovered with the chlorate or chlorite.

The salt which is added should be introduced in an amount which is equivalent to half of the alkali reacted. With this relationship, an amount of metal ion is introduced which is equal to the amount of chlorite ion which is formed so that all of this introduced cation appears as the chlorite.

If a chlorate is to be utilized in carrying out the process according to the mode represented by Equations *g* and *h*, one possible source of the chlorate ion is the products resulting from carrying out a separate chlorine dioxide absorption reaction. The products of this second chlorine dioxide absorption reaction, after the alkali has been neutralized, are combined with the products resulting from the absorption by the first alkali of chlorine dioxide. This is represented by the equations:

It will be observed from Equations *i*, *j*, and *k* that an equivalent amount of alkali is consumed in the two reactions represented by Equations *i* and *j*. It is not necessary that the alkalis employed in the reactions of Equations *i* and *j* have the same anion, as the one may be a hydroxide and the other may be a carbonate, for example. Also, as explained in connection with Equations

b and *c*, the process may be carried out employing any two different metals of the alkali metals, alkaline earth metals or magnesium, the stated precautions as to the selection of the cations and the anions in the system being observed.

According to a third mode of carrying out the invention, the metal of the alkali chosen to carry out the absorption reaction is not the metal of either the desired chlorate or the desired chlorite, but is chosen principally because of the inexpensiveness of this alkali. The metal of the desired chlorate is introduced by one salt and the metal of the desired chlorite is introduced by another salt. Both of these salts are added to the products of the absorption reaction after the alkali is neutralized and before those products of the absorption reaction are separated.

For example, it may be desired to obtain potassium chlorate and sodium chlorite, without the use of an alkali of either of these metals. This may be accomplished by using as the alkali, an inexpensive compound as calcium hydroxide and, after the hydroxide is neutralized, adding the salts which are to introduce the metals of the desired chlorate and chlorite. This is represented by the equations:

From Equations *l* and *m*, it will be noted that an amount of each salt is added which is equivalent to half of the alkali employed. This results in the addition of one metal in an amount equivalent to the chlorate ion formation so that all of this metal is used in the formation of the desired chlorate. Also, it results in the addition of another metal in an amount equivalent to the chlorite ion formation so that all of this other metal is used in the formation of the desired chlorite.

It is not necessary that the two added salts have the same anion, as, for example, one may be a sulfate and the other a nitrate. If it is desired that the foreign salt product be separated from the chlorate and chlorite, it is preferable that the anion or anions of the added salts be such as to form with the metal of the alkali, a salt product of quite different solubility from the chlorate and chlorite. However, this salt product may be left with either the chlorate or the chlorite and if this is to be done, it may or may not have a solubility close to the solubility of the chlorate or chlorite with which it is to appear.

The above stated precautions as to the anions and cations in the system, should be observed to assure the formation of the desired products. For example, if sodium chlorate is desired, the potassium ion should not be introduced into the system.

It will be appreciated that a mixture of chlorites, for example, rather than a single chlorite, could be produced by this invention simply by the use of two or more alkaline compounds, or by the use of one alkaline compound and the salts of two or more metals. In this way, the necessary metals for the formation of the mixture of chlorites are introduced.

Although the oxides, hydroxides, and carbonates of the alkali metals, the alkaline earth metals, and magnesium have been mentioned as the alkaline compounds useful for the operation of the invention, the reaction rate is much slower when carbonates are used than it is when oxides or hydroxides are employed. It is for this rea-

son that the oxides and hydroxides are the preferred alkaline materials.

In carrying out the process of this invention in the preferred manner, chlorine dioxide as a dilute gas in the presence of such a diluent as air or nitrogen, is reacted with an aqueous slurry or solution, as the case may be, of the desired alkaline material. This chlorine dioxide is introduced as a dilute gas to prevent the decomposition of the chlorine dioxide. A suitable concentration of chlorine dioxide in the gas phase is about 5% by volume. This concentration depends somewhat upon the temperature employed in the reaction, the lower the temperature, the higher the safe concentration of chlorine dioxide which can be allowed. The temperature of the reaction can be varied from the freezing point to 100° C., a suitable temperature being 50° C. The reaction rate increases with higher temperatures.

The quantity of water used for the reacting slurry or solution is not vital to the operation of the invention and may be varied over a wide range. In general, sufficient water should be present at the end of the operation, and before the products are separated, to keep the chlorate and chlorite in solution and thereby prevent their precipitation along with the precipitation of the third compound, if present, providing that it be desired to allow the third compound to be precipitated for removal from the chlorate-chlorite solution. If the invention is to be operated so that only a chlorate and a chlorite are produced, and no foreign salt is to be produced, it will be evident that it is only necessary to have sufficient water present to keep these two compounds in solution. However, if potassium chlorate be one of the compounds produced, for example, the amount of water present may be reduced so as to cause the precipitation of some of the potassium chlorate. It further will be realized that should a compound, which it is desired to keep in solution, be inadvertently precipitated, additional water may be added to redissolve it.

In general, the amount of water in the reaction vessel, wherein chlorine dioxide is being absorbed, should be enough to make the gas-liquid contact efficient. If too thick a slurry is used, difficulty may be experienced in retaining a uniform suspension and in obtaining proper contact between the chlorine dioxide gas and the absorbing medium. Design of the apparatus for the absorption of chlorine dioxide will dictate to a large degree the optimum thickness of slurry and, therefore, the quantity of water to be used. For most purposes, a suitable concentration of reactants is about 15% by weight in the water slurry or solution. This quantity of water, for example, will keep all of the potassium chlorate of a solution containing equal moles of potassium chlorate and sodium chlorite in solution at 25° C.

After the reaction has been completed, the mixture of final products is removed from the reactor for further treatment to separate the desired products. Inasmuch as the reactants and the products have been selected, as previously described, because of their mutually different solubilities in any given system, the separation of the various products will entail the use of such common chemical engineering unit operations as evaporation, crystallization, washing, and filtration.

This invention can be illustrated further and

explained by the following example, reference being had to the accompanying drawing:

In an absorber 1 is placed 56.1 parts of potassium hydroxide, and in a separate absorber 2 is placed 40 parts of sodium hydroxide, sufficient water being used to bring them into solution. Chlorine dioxide is introduced into both absorbers as a 5% by volume mixture with air. The reaction is continued in each absorber until the hydroxide is substantially neutralized.

After both absorption reactions are completed their products are combined into the mixer 3. It will be appreciated that this may be a separate vessel, or that the products of the one absorber may as well be delivered into the other absorber. After an intimate intermingling of these products, they are delivered to the evaporator 4. Evaporation is continued until the solution is saturated with respect to sodium chlorite at 25° C.

After cooling to about 25° C., the slurry from evaporator 4 is delivered to filter 5. About 90% of the 122.5 parts of potassium chlorate formed is recovered in the filter cake, and the filtrate contains all of the sodium chlorite and the residual potassium chlorate. These separated products may be dried.

Related subject matter is disclosed in my pending cases as follows: Ser. No. 647,403, filed February 13, 1946, directed to perchlorate production; Ser. Nos. 647,404, filed February 13, 1946, and 659,043, filed April 2, 1946, directed to the production of chlorates and chlorites; Ser. No. 647,396, filed February 13, 1946, directed to the production of perchlorates and involving the production of chlorates; and Ser. Nos. 736,113, filed March 20, 1947, 756,542, 756,543, and 756,544, filed June 23, 1947, directed to the separation of salts in salt systems containing a chlorate and a chlorite.

Having thus described the invention, I claim:

1. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with a salt whose metal is a different one selected from said class, whereby substantially all of one of the metals introduced appears as the chlorate while substantially all of the different metal appears as the chlorite, said salt being so selected that the anion thereof does not form an insoluble compound with the metal whose chlorate is desired, and said compound and said salt being so selected that no potassium ion is present when a chlorate other than that of potassium is desired.

2. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation

75

thereof, with a salt of the metal whose chlorate is desired, whereby substantially all of this latter metal appears as the chlorate, said salt being so selected that the anion thereof does not form an insoluble compound with the metal whose chlorate is desired, and said compound and said salt being so selected that no potassium ion is present when a chlorate other than that of potassium is desired.

3. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with a salt of the metal whose chlorate is desired, whereby substantially all of this metal appears as the chlorate, said salt being introduced in an amount equivalent to half the compound introduced, said salt being so selected that the anion thereof does not form an insoluble compound with the metal whose chlorate is desired, and said compound and said salt being so selected that no potassium ion is present when a chlorate other than that of potassium is desired.

4. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with a chlorate whose metal is a different one selected from said class, whereby the metal of said compound appears as the metal of this introduced chlorate ion, and said compound and said chlorate being so selected that no potassium ion is present when a chlorate other than that of potassium is desired.

5. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with a chlorate whose metal is a different one selected from said class, whereby the metal of said compound appears as the metal of this introduced chlorate ion, said chlorate being added in an amount equivalent to half the introduced compound, and said compound and said chlorate being so selected that no potassium ion is present when a chlorate other than that of potassium is desired.

6. The process of forming a chlorate of a metal selected from the class consisting of lithium, potassium, sodium, calcium, barium, strontium, and

magnesium, and for forming therewith a chlorite of a different metal selected from said class, comprising reacting chlorine dioxide and a compound selected from the group consisting of hydroxides and carbonates, the metal of the selected compound being that of the desired chlorate, and, after the reaction is substantially completed, combining the reaction products, without separation thereof, with a salt whose metal is selected from

10 said class and whose chlorite is desired, whereby substantially all of the metal introduced as the salt appears as the chlorite, said salt being so selected that the anion thereof does not form an insoluble compound with the metal whose chlorate is desired, and said compound and said salt being so selected that no potassium ion is present when a chlorate other than that of potassium is desired.

7. The process of forming a chlorate of a metal 20 selected from the class consisting of lithium, potassium, sodium, calcium, barium, strontium, and magnesium, and for forming therewith a chlorite of a different metal selected from said class, comprising reacting chlorine dioxide and a compound

25 selected from the group consisting of hydroxides and carbonates, the metal of the selected compound being that of the desired chlorate, and, after the reaction is substantially completed, combining the reaction products, without separation

30 thereof, with a salt whose metal is selected from said class and whose chlorite is desired, whereby substantially all of the metal introduced as the compound appears as the chlorite, said salt being added in an amount equivalent to half the compound introduced, said salt being so selected that the anion thereof does not form an insoluble compound with the metal whose chlorate is desired, and said compound and said salt being so selected that no potassium ion is present when a chlorate

40 other than that of potassium is desired.

8. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substan-

45 tially completed, combining the chlorate and chlorite, without separation thereof, with the unseparated chlorate and chlorite resulting from the reaction of chlorine dioxide with a compound whose metal is a different one selected from said class, whereby the major portion of the metal of the one compound appears as a chlorate and the major portion of the metal of the other com-

50 pound appears as a chlorite, and said compounds being so selected that no potassium ion is present when a chlorate other than that of potassium is desired.

9. The process of forming a chlorate of a metal 60 selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substan-

75 tially completed, combining the chlorate and chlorite, without separation thereof, with the unseparated chlorate and chlorite resulting from the reaction of chlorine dioxide with a compound whose metal is a different one selected from said class, whereby the major portion of the metal of the one compound appears as a chlorate and the major portion of the metal of the other com-

tially completed, combining the chlorate and chlorite, without separation thereof, with the un-separated reaction products resulting from the reaction of chlorine dioxide with a compound whose metal is a different one selected from said class, whereby the major portion of the metal of the one compound appears as a chlorate and the major portion of the metal of the other compound appears as a chlorite, the two chlorates being utilized in equal amounts on an equivalent basis, and said compounds being so selected that no potassium ion is present when a chlorate other than that of potassium is desired.

10. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with a chlorite of a metal whose chlorate is desired, whereby substantially all of this latter metal appears as the chlorate and all of the metal of the compound appears as a chlorite, and said compound and said chlorite being so selected that no potassium ion is present when a chlorate other than potassium is desired.

11. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with a chlorite of a metal whose chlorate is desired, whereby substantially all of this latter metal appears as the chlorate and all of the metal of the compound appears as a chlorite, said chlorite being introduced in an amount equivalent to half the compound introduced, and said compound and said chlorite being so selected that no potassium ion is present when a chlorate other than potassium is desired.

12. The process of forming a chlorate of a metal selected from the class consisting of lithium, potassium, sodium, calcium, barium, strontium, and magnesium, and for forming therewith a chlorite

of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with two salts, the metal of one salt

10 being that of the desired chlorate and the metal of the other salt being that of the desired chlorite, the metals of these salts being different from each other and from the metal of said compound but being selected from said class, said salts being so selected that the anions thereof do not form insoluble compounds with the metal whose chlorate is desired, and said compound and said salts being so selected that no potassium ion is present when a chlorate other than that of potassium is desired.

13. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with two salts, the metal of one salt

25 being that of the desired chlorate and the metal of the other salt being that of the desired chlorite, the metals of these salts being different from each other and from the metal of said compound but being selected from said class, each of said salts being introduced in an amount equivalent to half the compound reacted, said salts being so selected

30 that the anions thereof do not form insoluble compounds with the metal whose chlorate is desired, and said compound and said salts being so selected that no potassium ion is present when a chlorate other than that of potassium is desired.

35 14. The process of forming a chlorate of a metal selected from the class consisting of lithium, potassium, sodium, calcium, barium, strontium, and magnesium, and for forming therewith a chlorite of a different metal selected from said class, comprising reacting chlorine dioxide and a compound selected from the group consisting of hydroxides and carbonates, and whose metal is selected from the class consisting of lithium, potassium, sodium, calcium, barium, strontium, and magnesium, and, after the reaction is substantially completed, combining the reaction products, without separation thereof, with two salts, the metal of one salt

40 being that of the desired chlorate and the metal of the other salt being that of the desired chlorite, the metals of these salts being different from each other and from the metal of said compound but being selected from said class, each of said salts being introduced in an amount equivalent to half the compound reacted, said salts being so selected

45 that the anions thereof do not form insoluble compounds with the metal whose chlorate is desired, and said compound and said salts being so selected that no potassium ion is present when a chlorate other than that of potassium is desired.
